GARRET P. BERGEN, OF BROOKLYN, NEW YORK.

Letters Patent No. 85,163, dated December 22, 1868.

IMPROVEMENT IN COMBINED SCISSORS-SHARPENER AND SCREW-DRIVER.

The Schedule referred to in these Letters Patent and making part of the same.

To all whom it may concern:

Be it known that I, GARRET P. BERGEN, of Brooklyn, in the county of Kings, and State of New York, have invented a new and useful Combined Scissors-Sharpener and Screw-Driver, of which the following is a full, clear, and exact description, reference being had to the accompanying drawing, forming part of this specification, and in which—

Figure 1 represents a view in perspective of my combined scissors-sharpener and screw-driver, and

Figure 2, a sectional view thereof in direction of the length of the handle.

Similar letters of reference indicate corresponding parts in both figures.

My invention consists of a combination, in the one instrument or implement, of a scissors-sharpener, a screw-driver point or blade, and a handle, arranged to apply to both, and whereby every facility is afforded for grinding or sharpening the scissors-blades and for tightening up or adjusting the screw on or with which they work, and which holds them together.

Referring to the accompanying drawing, A represents a bevelled-edged file, and B, a circular guide-piece, the two constituting a scissors-sharpener substantially of the character described in Letters Patent of the United States, No. 72,995, issued to Lucien M. Gilbert on the 7th day of January, 1868, and assigned to myself and Charles T. Bainbridge, September 8, 1868, and which operates to grind or sharpen the scissors, by drawing either blade of the latter across the file, with the flat side of the blade resting against the circular guide-piece.

C is a handle, arranged to project from the back of the guide-piece B, in the axial line thereof, and which not only facilitates the holding of the scissors-sharpener while in use, but also serves as a handle to a screw-driver point or blade, D, arranged to project in

front of the file A at its centre. This screw-driver blade is formed by a projection from or on the head of a wood-screw, E, which, on being screwed into the handle, answers to hold the scissors-sharpener to the latter, the guide-piece B being made to form a hollow rivet, a, through the eye of the file, for uniting the guide-piece and file together, and which hollow rivet serves as a bearing for the head of the screw, in and by the one process of fastening, to secure the scissors-sharpener and screw-driver blade to the handle. This forms a very simple and firm mode of fastening, with every facility for renewal either of the screw-driver blade or scissors-sharpener, when necessary.

By combining, in the one implement, a scissors-sharpener and screw-driver, there is a great convenience and advantage, inasmuch as after sharpening scissors, and at other periods, it frequently is necessary to tighten up or adjust the joint-screw that unites their blades, or if necessary, the blades may be detached for sharpening, and afterwards put together again.

The whole device constitutes but a small appendage to the work-basket, and apart from the convenience of the combination in a general way, much time will be economized by not having first to look for a scissors-sharpener, and afterwards for a screw-driver, to put the scissors in proper working-order.

What is here claimed, and desired to be secured by Letters Patent, is—

The combination, in the one instrument or implement, of a scissors-sharpener, A and B, a screw-driver point or blade, D, and a handle C, substantially as described.

GARRET P. BERGEN.
